 International Business Machines Corporation,
 New York, N. Y., a corporation of New York

Application January 26, 1940, Serial No. 315,733

3 Claims. (Cl. 197—126)

This invention relates to typewriting machines and more particularly to that class of machine adapted for using fanfold continuous forms.

The object of the present invention is to provide novel means for splitting the folds of a fanfold web in a machine of the general type disclosed in Patent No. 1,132,055. In the present case, the invention is disclosed as applied to a continuous billing machine similar to the one described and claimed in application Serial No. 127,684, filed February 25, 1937, by G. H. Beiderbecke. However, it will be understood that the invention is capable of general application and not limited in its use to the structure disclosed in the above patent or the one disclosed in aforementioned application.

An object is to provide a web splitter which at will can be placed in any desired position on the carbon sheet anchoring blade to accommodate forms of different widths without requiring the use of tools.

Another object is to provide a web splitter which has a relatively thin sharp edge so as to have a high efficiency in splitting the webs.

An object is to provide a splitter adapted to guide the forms by cooperating with the insides of the folds.

An object is to provide a combined splitter and carbon sheet anchoring clip.

Further objects of the instant invention reside in any novel feature of construction or operation or novel combination of parts present in the embodiment of the invention described and shown in the accompanying drawings whether within or without the scope of the appended claims and irrespective of other specific statements as to the scope of the invention contained herein.

In the drawings:

Fig. 1 is a plan view of the machine showing the splitter in place on the blades of the carbon stripping truck.

Fig. 2 is a large scale plan view, partly broken away, showing a carbon sheet anchored to a carbon blade by means of the combined splitter and carbon sheet anchoring clip comprising the present invention.

Fig. 3 is a vertical section of the line 3—3 on Fig. 2.

Fig. 4 is a plan view somewhat similar to Fig. 2 but shows the combined splitter and carbon sheet anchoring clip positioned to render the splitter ineffective to split the fold of a web.

Fig. 5 is a view similar to Fig. 2 but showing

a modification in which a circular cutter is used as a splitter.

Fig. 6 is a view of the right-hand end of the combined web splitter and carbon sheet anchoring clip disclosed in Fig. 5.

In Fig. 1, there is shown in plan view a continuous billing machine including a typewriter 10 and a carbon stripper carriage 11 which is reciprocable toward and away from the typewriter carriage 12 on a track 13. This track is removably attached at its front or left-hand end (Fig. 1) to a rod 14 forming part of the carriage. The truck 11 is provided with some means, such as a handle 15, by means of which the truck 11 may be moved rearwardly of the carriage or to the right (Fig. 1) to retract carbon sheets anchored to the truck 11. The track 13 is movably supported near its rear end upon a rail 16 which forms part of a framework 17 removably attached at 18 to the base of the typewriter 10. The track 13 is mounted on the rail 16 by means of anti-friction rollers 19 carried by a bracket 20 secured to the underside of the track 13 and is provided with a toothed stop bar 21 having adjustable stops like 22 to limit the travel of the truck 11.

Removably mounted on the truck 11 is a bar 23 having two posts 24 which provide a means of mounting the carbon sheet anchoring blades 25 on the truck 11. In the present case, each blade 25 is slotted at both ends to receive the posts 24 whereby the blade is held stationary with respect to bar 23 at both ends but is movable with truck 11.

The fanfold forms 26 are led from a suitable stack (not shown) beneath the right-hand end of the track 13 upwardly and over tube 27 on which are adjustably slidably mounted slide guides 28 for the edges of the forms. Thence, the now separated plies of the forms pass between the blades 25, the carbon sheets 26a, over the top of the truck 11, and around the platen 29 which is rotatably mounted in the carriage. The platen, as usual in such machines, is displaceably mounted so as to be movable to a position to permit the forms 26 to be straightened as a preliminary to retracting the carbon sheets 26a by rearward movement of the truck 11 effected by means of the handle 15 in a well known way. Since, in the present case, the blades 25 must pass through the folds of the fanfold web, it will be understood that in loading the machine, the side folds between the first few sets of forms are split back along the line of fold far enough from the leading edges

of the first set of forms to permit the blades 25 and the attached carbon sheets 26a to be inserted. The structure so far described is now well known in the art and is the same as the structure disclosed in aforesaid Beiderbecke application.

The operation of such a machine is well known in the art; however, a brief explanation will be given to enable the action of the splitter blades hereinafter to be described to be more readily understood. It will be assumed that Fig. 1 shows the condition of the machine when it is in readiness for typing the first set of a package of continuous forms, with the carbon stripper truck 11 fully retracted. While the forms are being typed line-by-line, the tension applied thereto and to the carbon sheets 26a by the line spacing movement of the platen 29 causes the truck 11 to be advanced step-by-step toward the platen, that is, toward the left in Fig. 1. After a set of forms has been completed, the operator raises the platen by lifting a hand lever 30 and grasps the leading edges of the forms with the right hand drawing them against an adjustable leading edge gauge 31. The operator next grasps the handle 15 with the left hand and pushes the truck 11 to the rear of the machine, that is, to the right in Fig. 1, as far as it will go. As well known, the leading edges 26b of the carbon sheets 26a terminate far enough short of the leading edges of the forms to permit the operator to grasp the forms without grasping the carbon sheets. After the carbon sheets have been fully retracted, the platen is lowered and the completed set of forms may be severed from the succeeding blank set by means of a tearing knife 31a provided for the purpose. To facilitate this operation, it is customary to provide the form webs with transverse rows of perforations between sets of forms.

For the purpose of anchoring the carbon sheets to the blades, it is customary to use clips of various kinds, the carbon sheet being folded around the blade and a clip pushed over the carbon sheet. When the forms are of the fanfold type, as has been assumed to be the case up to the present point, it is common practice to provide some means to split the folds apart so that, when a completed set of forms is severed, some at least of the forms will be severed as loose sheets and will not require a second severing operation after the first.

The present invention contemplates the provision of a combination splitter and carbon sheet anchoring clip which will simplify the procedure in loading the machine and reduce the number of special parts required. One form which the combined splitter and carbon sheet anchoring clip may take is illustrated in Figs. 1 to 4.

The splitter body may comprise two thin sheet metal members 32 (Figs. 2 and 3) which may be secured together along the edge 32a by any suitable means such as welding, soldering, or riveting. Secured between the two members 32, as clearly shown in Fig. 3, is a cutter blade 33 which is thin and narrow and is substantially uniform in width and thickness, except at its right-hand end (Fig. 2). This end of the blade 33 is formed like the barb of a fish-hook with the web splitting portion 33a formed as a cutting edge making an acute angle with the longitudinal axis of the blade 33 and the barbed portion extends upwardly between the members 32. Above the cutting portion 33a, the members 32 are so shaped as to form web guide portions 32b designed to run inside the fold which is to be split by the cutting

edge 33a. For this purpose, the portions 32b each has a straight edge 32c extending upwardly from the cutting edge 33a at right angles to the axis of the blade 33 and which terminates in a rounded edge designed to slide smoothly along the line of fold so as to hold the line of fold straight and guide the fold to the cutting edge 33a.

The edges 32d opposite the edges 32a are flared, as shown most clearly in Fig. 3, to facilitate placing the splitter on the blade 25. The carbon sheets 26a are folded or looped about the bar 25 for a short portion of their length and the combined splitter and carbon sheet anchoring clip is pressed on the bar over the fold of the carbon sheet as shown in Fig. 3. The lower edge of the blade 33, by abutting against the upper edge of the blade 25, acts as a stop to prevent pinching the carbon sheets so tightly as to make them liable to be torn, and also functions as a means of squaring the edges 32c of the guide portions 32b with the fold of the web with which they cooperate.

When it is desired to split folds, the combined web splitter and clip is positioned in relation to the fold in the web as shown in Fig. 2 whereby the cutting edge 33a projects well beyond the line of fold with the portion 32b engaging the fold to be split. It may be desired to split some folds and not others and for that purpose the combination splitter may be set in relation to the line of fold as in Fig. 4 wherein the cutting edge 33a is completely inside the fold and ineffective.

As shown in Fig. 3, the members 32 are folded longitudinally along lines coinciding substantially with the upper edge of the blade 25 and the lower edge of the blade 33, which is relatively thinner than the blade 25, whereby the sides of the combination clip evenly press the carbon sheet against sides of the blade 25. The members 32 are also similarly folded around the upper edge of the straight portion of blade 33 and around a part of the cutting portion 33a. In Fig. 1, two of the combination clips are shown disposed to properly split folds which are opposite each other, the position of the splitters being alternated to cooperate with alternate folds of the webs.

In Figs. 5 and 6, there is shown a modified form of combination clip and splitter, the clip body in this case comprising two strips 34 which are secured together along their upper edges and folded around a blade 35 of substantially the same length, width, and thickness as the blade 33 but differing from the latter in not having a cutting edge. The members 34 instead of having their lower edges flared and continuous as in Fig. 2 may be formed with portions 34a which are shaped in section like the members 32 but are spaced along the bar at intervals to provide a plurality of clip elements for engaging the carbon sheet and holding it securely on the bar. The members 34 each have upward extensions 34b somewhat similar to the portions 32b in Fig. 2 but are formed as most clearly shown in Fig. 6 to provide an open space in which is mounted a circular cutter 36. This cutter has a fairly sharp edge and is rotatably mounted on a rivet 37 passing through both of the members 34. The cutter 36 engages a line of fold guided by the portion 34b and splits the fold apart, being rotated in the process by friction between the edges of the forms and the sides of the blade so as to always present a fresh cutting surface to the fold to be split.

The form of the combination splitter shown in

Figs. 5 and 6 is particularly suited for fanfold forms which are not perforated along the lines of fold to facilitate splitting the forms. The form shown in Figs. 2 and 3 may be used to split forms which are not perforated along the line of fold but is less well adapted for this purpose since the wear on the blade always comes at the same spot and therefore the blade will tend to become dull much quicker than the circular cutter 36.

While there has been shown and described and pointed out the fundamental novel features of the invention as applied to a preferred embodiment and one modification thereof it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In combination with a transfer sheet support bar projecting into the fold of a fan folded web, a unitary clip assembly including a clip body and a web splitting element secured to the clip body and operative to split the web along the line of the fold in the web, said clip body being adapted to frictionally clasp a transfer sheet lying in said fold to said bar and, adjacent said splitting element, formed with a web guiding portion having a straight edge extending parallel with and contacting line of said fold to guide the fold in a straight line to said splitting element.

2. In combination with a movable transfer sheet support bar projecting into a fold to be split, a main clip body having portions thereof acting as a clip to clasp to the bar a transfer sheet located in said fold and looped around said bar, said clip body being movable longitudinally of the bar to adjust the position of the clip body, said clip body also having a web splitter adjustable into active position to split said fold at the line of fold by the longitudinal movement of the clip body on said bar, said clip body being formed with a guide portion adjacent the web splitter for guiding the line of fold to the splitter, said guide portion being located inside the fold and extending substantially parallel with the line of fold and in contact therewith to guide the line of fold to the splitter in a straight line parallel with the line of movement of said bar.
3. In combination with a manifolding transfer sheet anchoring member, a combination web splitter and clip having web splitting means and means for clipping the transfer sheet to said member to frictionally hold the transfer sheet on said member so as to be adjustable on said member from an active position in cooperation with the line of fold of a web to be split to an inactive position out of cooperation with the line of fold to be split, said splitter and clip having a web guiding extension having a straight portion parallel with the line of fold designed to ride along the inside of the fold and in close contact with the line of fold to guide the fan folded web in a straight line to the splitting means.

CARLTON T. JACKSON.
